(57) **CLAIM**

The ornamental design for an insulated battery boot, as shown and described.

DESCRIPTION

FIG. 1 is a perspective view of an insulated battery boot according to an embodiment of the invention disposed on a representation of a hand battery powered tool.

FIG. 2 is a first side elevational view of an insulated battery boot according to an embodiment of the invention.

FIG. 3 is a second, opposed side elevational view of an insulated battery boot according to an embodiment of the invention.

FIG. 4 is a rear end elevational view of an insulated battery boot according to an embodiment of the invention.

FIG. 5 is a front end elevational view of an insulated battery boot according to an embodiment of the invention.

FIG. 6 is a top planform view of an insulated battery boot according to an embodiment of the invention; and,

FIG. 7 is a bottom planform view of an insulated battery boot according to an embodiment of the invention.

The broken lines shown in the drawing represent stitching.
